UNITED STATES PATENT OFFICE.

NIKLAS SCHILZONYI, OF WHITTIER, CALIFORNIA.

MUSICAL PIPE INSTRUMENT.

1,169,358.

Specification of Letters Patent. Patented Jan. 25, 1916.

Application filed April 16, 1913. Serial No. 761,618.

To all whom it may concern:

Be it known that I, NIKLAS SCHILZONYI, a citizen of the United States, residing at Whittier, in the county of Los Angeles and State of California, have invented a new and useful Musical Pipe Instrument, of which the following is a specification.

This invention relates to mouth blown musical pipe instruments and may be embodied in instruments having a single reed for each mouth, thus resembling instruments of the clarinet family, that is to say, clarinets, saxophones and the like; and may also be embodied in instruments having a plurality of reeds for each mouth as is the case with double reed instruments such as oboes, bassoons and the like; and it may also be embodied in instruments of the flageolet family.

20 The invention is pioneer in that I provide a musical mouth blown pipe instrument which is capable of being played by one person using both hands and which will produce two sounds at the same time and in

25 which the sounds of simultaneously played notes may differ in color, in range and in tone quality, and may be played in any interval of the full chromatic scale of two or more octaves, as the intervals of seconds,

30 thirds, fourths, etc., at the will of the player. An object is to give a richer color effect by a single player than was heretofore possible and to increase the orchestral effect with a given number of players.

35 Further objects and advantages may appear from the subjoined detail description.

The invention may be embodied in various forms and with various numbers of vents and arrangements of keys and it is not 40 deemed necessary to show and specifically describe each of the various forms and arrangements.

The invention involves various basic and original features among which may be particularly mentioned, the arrangement in a 45 reed instrument of vents and keys whereby the full chromatic scale of two or more octaves can be executed on one tube by one hand of the player, and whereby said full 50 chromatic scale of two or more octaves can be played throughout with either single or double notes at the will of the player blowing through the single mouthpiece and the playing with the fingers of one or both notes.

Another basic feature is the construction 55 whereby two full chromatic scales can be played on the same instrument at the same time, thus introducing the wind instrument above referred to, into a wider field of solo performance and enabling the soloist on a 60 mouth played pipe instrument to produce double toned effects after the manner of violins and other string instruments.

A further basic feature of the invention is the combination in a single mouth blown 65 pipe instrument, of a cylindrical and a taper tube thus simultaneously giving the color effects of instruments corresponding respectively to the clarinet and the saxophone.

It is to be assumed in reading the accompanying drawings that the vents are only 70 approximately placed; it being left to the skill of the manufacturer to tune the instrument by properly arranging the vents along and proportioning them to the bore and to 75 each other; the A sharp vents being of the usual reduced size so as to serve as the octave vents.

The accompanying drawings illustrate 80 the invention in four forms of instrument known respectively as the duonett, the duophone, the saxonett and the clariphone; all being of the clarinet family.

Figure 1 is a fragmental or top view of a 85 duonett constructed in accordance with this invention. Fig. 2 is a back or bottom view of the duonett shown in Fig. 1, the reeds and their band being broken to expose the reed seats and the mouths or wind holes in the mouth-piece. Fig. 3 is a front view partly 90 in section of a duophone constructed in accordance with the invention. Fig. 4 is a fragmental back or bottom view of the duophone shown in Fig. 3. Fig. 5 is an enlarged cross-section on line x^x , Fig. 1. Fig. 95 6 is a front view of a saxonett. Fig. 7 is a front view of a clariphone. Fig. 8 is an enlarged fragmental view illustrating in part the finger-piece arrangement of the right pipe of the duonett. Fig. 9 is an enlarged 100 fragmental view illustrating in part the finger-piece arrangement of the left pipe of the duonett. Fig. 10 is an elevation of the group of overlapping finger-pieces shown in Fig. 9. Fig. 11 is an enlarged detail to 105 illustrate the extensible keys.

The views are more or less of a diagrammatic character.

Referring first to the instrument shown in Figs. 1 and 2, the sound-producing means comprises a mouth-piece 50 provided with two reed-covered mouths or wind holes 51, 51' communicating respectively with the flues 52, 52' that terminate in sockets 53, 53' that receive the reduced ends 54, 54' of the right and left pipes or tubes 55, 55' that are held together and spaced apart by the bands 56, 57. The mouth-piece 50 constituting means for introducing air to both tubes is provided between the mouths 51, 51' with a rib 58 on opposite sides of which are mounted the reeds 59, 59' that rest on flat seats 60, 60' at opposite sides of said rib 58. The reeds are fastened to the mouth-piece by the reed band 61 in the usual manner of securing reeds to clarinet mouth-pieces. The mouth-piece in the present instance is one solid piece and the portion between the mouths 51 and 51' is so formed that the wind cannot escape therebetween. The rib 58 positioned between said mouths further prevents escape of wind between said mouths and between the reeds 59 and 59' whereby the reeds will be properly vibrated. The flues 52, 52' in the mouth piece diverge from the mouths 51, 51' and communicate with the voicing pipe channels or bores 62, 62' respectively in register therewith, so that when the reduced ends 54, 54' of the tubes are inserted into the sockets, the adjacent sides of said tubes will be parallel with each other, thus bringing the instrument into a compact and convenient form. The bell ends of the tubes may be provided with spigots 63, 63' for two bells not shown, or for one bell 64 which is provided with two sockets 65, 65', to receive said spigots or tube ends 63, 63'.

Each of the tubes is provided with the usual finger and key holes or vents to determine the speaking lengths of the tubes, and said vents are marked in the drawings with the characters E, F#, F, G#, G, A#, A, B, C, C#, D, D#, E', F', F#, G', G#, A' and A#' for the right tube and g, g#, a, a#, b, c#, c, d#, d, e, f, f#, g', g#, a', a#, b', c', c#, representing full chromatic scales of the lower register; said characters being connected with leaders pointing toward said vents; the characters for the second octave of each tube being distinguished by an index. The vents are digitally controlled directly or by keys. While the instrument is at rest, as on the table or while not being manipulated by the hand, some of the vents are normally open and others are normally closed. The normally-closed vents and their keys are indicated by black dots and the normally open vents and their keys are indicated by circles. For playing the upper register of said scales the octave keys A#' and a#' are kept open by the thumb while the scales are played by the fingers.

The finger pieces for said keys are designated by Arabic numerals from 1 to 15 for the right tube, and from 1'' to 14'' for the left tube, the vents B, A, G, and b, a, g, being controlled directly by the fingers; and the notes C, and c being open notes. The vents A#' and a#' are the octave holes which are held open while the notes A sharp are sounded and are also held open while the higher scales are being played by over blowing.

The construction of the keys is indicated in a diagrammatic manner, and it is understood that they may be extensible for adjustment to long or short fingers, and that the normally-closed vents are opened by pressure of the fingers or thumbs, as the case may be, upon the finger-pieces of the keys that control such vents, while the normally open vents are closed by pressure upon the keys controlling such vents, or by digits applied directly to the vents.

The finger pieces of the right keys 6, 8, 11 and 13 for C#, D#, F# and G# are grouped together and finger-piece 8 overlaps finger piece 6; finger piece 14 overlaps finger piece 8, and finger piece 13 overlaps finger piece 11; so that when 13 is pressed down by the first finger of the right hand, vents C#, D#, F# and G# are all open, thus giving the note G sharp, and may be successively closed to sound F sharp, D sharp and C sharp, by simply shifting the first finger from 13 to 11, 11 to 8, 8 to 6 and then off of 6. The same is the case with the grouped keys 7, 9, 10, 12, 14 which overlap in the order named and are operated by the first finger to open their normally closed vents.

The keys 5'', 4'', 3'', 2'' and 1'' are also grouped together and are overlapped in the order named and their normally open vents may all be closed by pressing down key 1'' by the fourth finger of the left hand, thus opening vent g and giving the note G; then by shifting the fourth finger to finger piece 2'', 3'', 4'' and 5'' successively the vents g#, a, a# and b are opened to give the notes G sharp, A, A sharp and B. Then releasing key 5'' gives C.

The rib 58 between the reeds enables the player to adjust his lip to the reeds discriminately so as to apply the air appropriately to the reed coverings of the separate mouths independently of each other; thus giving a wide field in which to exercise the skill of the player in either the clarinet type, or the bassoon type of instrument.

The right tube 55 is played with the right hand only, and the left tube 55' with the left hand only. In the right tube the lower section has eight vents E, F#, F, G#, G, A#, A and B, and the upper section ten vents C#, D, D#, E', F', F#, G', G#, A' and A#'; C, being the natural or open note,

sounded when the fingers and thumb of the right hand are not in action, and the open vent B determining the note.

Still referring to Figs. 1 and 2, it will be noted that the five vents B, A, G, F and E on the right tube 55 are normally open and all the other vents on the right tube are normally closed; and it will be understood that in order to give the lowest note of said tube 55, all the vents of said tube must be closed; and said normally open vents therefore, are closed by pressing the thumb on the finger-piece 1, the fourth finger on the finger-piece 2 of the F key, and the other three fingers of the right hand on the normally open vents B, A, G. While blowing the instrument the right thumb being on the key at the back of the right tube, and the first second and third fingers on the front vents B, A and G and the fourth finger on the key 1, thus closing the front vent F, the vents of the entire tube are closed and said lowest note E of the right tube will be sounded; then releasing the thumb and leaving the four fingers down gives F natural; then pressing the thumb on the next key 3, at the back of the instrument gives F sharp; releasing the same key with the thumb and fourth finger together, gives G natural; then pressing key 4 with the fourth finger gives G sharp; then releasing the third and fourth finger gives A natural; then pressing down key 5 with the third finger gives A sharp; then releasing the second and third finger gives B natural and then releasing the first finger gives C natural. From the note C upward the first finger will operate keys 6, 7, 8, 9, 10, 11, 12, 13 and 14 for the following notes respectively C sharp, D, D sharp, E, F, F sharp, G, G sharp and A. Key 15 on the back of the right tube may then also be opened by pressing the right thumb thereon, thus adding the note A sharp; then releasing the other keys and covering the entire lower section of the instrument while vent A[#] is open, gives the note B, and then opening the lowest key 1 with the thumb gives C; pressing the key 3 on the back with the thumb gives C sharp; releasing the thumb and the fourth finger gives D; pressing the key 4 by the fourth finger gives D sharp; releasing the third and fourth finger gives E; pressing key 5 with the third finger gives F; releasing the second and third finger gives F sharp; and releasing the first finger gives G. From here up the first finger will be used as before for G sharp, A, A sharp, B, C, C sharp, D, D sharp E of the upper octave. The left tube 55' is operated entirely with the left-hand, the lower section thereof having five normally open vents g, g[#], a, a[#] and b operated by keys 1'', 2'', 3'', 4'' and 5''. Closing vent g' in the back 65 with the left thumb and the vents e, d and c

at the front of the instrument with the first, second and third fingers as indicated by the marks 1st, 2nd and 3rd; and the lowest key 1'' with the fourth finger thus closing all the vents of the left tube while sounding the instrument gives the note G on the left tube. Then the chromatic scale will be played by releasing keys 1'', 2'', 3'', 4'' and 5'' successively by shifting the fourth finger from key to key and finally releasing the fourth finger thus giving the notes from G sharp to C natural. During this the third, second and first fingers continue to close the vents c, d, e, respectively, and the thumb closes vent g. Now pressing key 6'' with the fourth finger gives the note C sharp; then releasing the third and fourth fingers from vents C and C[#] gives the note D; then pressing key 7'' with the third finger gives D sharp; releasing the second and third fingers from vents d and d[#] gives E. Releasing first finger from vent e and pressing the second finger gives the note F; releasing the second finger from its vent gives F sharp; then releasing the thumb from vent g' gives the note G; then pressing the first finger on the side key 8'' gives G sharp; then pressing the first finger on the next key 9'' gives A, then pressing the thumb on the key 10'' thus keeping 9'' and 10'' open gives A[#]; then shifting the thumb up and thus also pressing key 11 gives B; then still pressing keys 1'', 10'' and 11'' and thus keeping the vents a', a[#]' and b' open pressing the finger on key 12'' gives C; then rocking the finger sidewise releasing 9'' and 12'' and pressing key 13'' thus opening the vents g[#], c[#]' in addition to vents a[#], b' gives C sharp. The key 11'' overlaps the key 10'' and the key 13'' overlaps 8'', and key 12'' overlaps key 9'' so that when either or all of keys 12'', 13'' and 11'' are pressed down, the vents a', c', g[#], c[#], a[#]' and b' will be open. Now releasing all the keys excepting key 10'', which serves as the octave key, the scale from C sharp up can be played by fingering as above described.

Now referring to Figs. 3 and 4 in which the duophone is illustrated, it will be noted that the vents on the right pipe are marked with the characters C, D, D[#], E, F, F[#], G, G[#], A, A[#], B, C', C[#]' and D' on the front, and with the characters B and C[#] on the back; and that the left pipe is marked on the front with characters d, d[#], e, f, f[#], g[#], a, a[#], b, b[#], d' and d[#]'. These characters respectively indicate the lower and higher notes on the scales that may be played on the instrument, the first run being made while keeping the octave vents 16, 17 closed, and the second run being made while pressing either or both of the octave keys 18, 19, thus opening either or both of the octave vents 16, 17 while the instrument is played by overblowing the same as de- 130

scribed in playing the duonett. The bore 20 of the duophone pipes are tapered after the manner of the bores in saxophones and like instruments. The vents B, C, D, E, 5 and F# of the right pipe and the vents d, d#, e, f, f#, g, a and b of the left tube are all normally open, while the vents C#, D#, F, G#, A, A#, B, C, C#, D' and 10 16 of the right pipe, and the vents g#, d', 11 d#' and 17 of the left pipe, are all normally closed. The keys 21 for vents C#, 22 for D#, 23 for F, 24 for G#, 25 for A, 26 for A#, 27 for B, 28 for C', 29 for C#, and 30 for D are all arranged to open the 15 normally closed vents when the keys are pressed; and the keys for the normally open vents are as follows: 31 for vent B, and 32 for vent C. The keys 18, 21 and 31 are grouped at the back of the right pipe to be 20 played by the right thumb. All the other keys of the right pipe are at the front side thereof. The keys 24, 26, and 29 are grouped together and overlapped in the order named and are played with the first 25 finger of the right hand, while keys 25, 27, 28 and 30 are grouped together and are overlapped in the order named and are also played with said first finger of the right hand. On the left pipe all the keys except 30 the octave key 19 are upon the front side of the pipe, the key 33 for vent d, 34 for d#, 35 for e, 36 for f, and 37 for f# are grouped and overlapped and are played by the fourth finger of the left hand for closing the normally open vents in the order named. Key 38 for opening vent g# is also played by the fourth finger of the left hand. Key 39 for vent a# is played with the third finger of the left hand. Keys 40 and 41 for vents 40 d' and d#' are both played with the first finger of the left hand. The normally open vents g, a, b of the left duophone pipe are closed by the third, second and first fingers of the left hand respectively. Referring 45 now to the saxonett shown in Fig. 6, the right tube 66 is constructed the same as the right tube 66 of the duophone shown in Figs. 3 and 4, while the left tube 55' corresponds to the left tube 55 shown in Figs. 50 1 and 2. The vents and keys therefor correspond to those of the tubes described with relation to Figs. 1, 2, 3 and 4. In the clariphone shown in Fig. 7, the right tube 55 is the same as the right tube 55 of the duophone shown in Figs. 1 and 2, while the left tube 66' of the clariphone is the same as the left tube 66' of the duophone shown in Figs. 55 3 and 4. Separate tubes shown in Figs. 6 and 7 are played in the same manner as the 60 corresponding tubes of the duonett and the duophone.

The parts upon which the fingers press for controlling the various vents are located so close together in the saxonett, Fig. 6, and 65 in the clariphone, Fig. 7, that all the notes

of the right tube, including a full chromatic scale of more than one octave, can be played by the right hand alone, and all the notes of the left tube, including a full chromatic scale of more than one octave can be played 70 by the left hand alone. The term "fingers" herein is intended to include the thumbs as well as the other digital members of the player's hands. I have, therefore, provided a pipe having the parts, as the rims of the 75 vents, or the finger pieces of the keys, upon which the fingers press for controlling the vents, located near together so that the vents of each tube or pipe can be controlled by the one hand devoted to playing that particular tube or pipe. These finger-pressed parts, including the vent rims and the finger pieces of the keys, are designated by characters as follows: In Fig. 6 the parts upon which the fingers press for controlling the 80 vents for producing the different notes are: for B, the character 70; for C, 71; C#, 72; D, 73; D#, 74; E, 75; F#, 76; G#, 77; A, 78; A#, 79; B', 80; C', 81; C#, 82; D', 83; g, 84; g#, 85; a, 86; a#, 87; b, 88; C#, 90; 89; c, 90; d, 91; d#, 92; e, 93; f#, 94; g#, 95; a', 96; a#, 97; b', 98; c, 99; c#, 100; and for the octave key 16, 101. In Fig. 7 the parts upon which the fingers press for controlling the vents respectively for producing the different notes are:—for the note E, the character 102; for F, 103; F#, 104; G, 105; G#, 105'; A, 106; A#, 107; B, 108; C#, 109; D, 110; D#, 111; E', 112; F', 113; F#, 114; G', 115; G#, 116; A', 117; 100 A#, 118; d, 119; d#, 120; e, 121; f, 122; f#, 123; g, 124; g#, 125; a, 126; a#, 127; b, 128; d, 129; d#, 130; and for the octave key 16, 131.

It is understood that the different parts 105 of the instrument may be made of any appropriate materials, as for instance, the cylindrical tubes 55 and 55' are shown as being made of wood, fiber, or any composition material; while the tapering tubes are 110 shown as being made of metal, but it is understood that the constructor may use such materials as he may deem advisable to produce the required tone qualities.

In Fig. 11 the extensible keys 6 and 7 indicate such an arrangement for any or all of the keys employed, no attempt having been made in the other views to show the extensible finger pieces, the object being to make provision whereby the same instrument 120 may be adjusted for use by players having longer or shorter fingers.

Attention is particularly directed to the fact that this invention broadly includes a mouth-blown musical pipe instrument comprising two tubes each having a wind-receiving mouth independent of the other and also having vents for a full chromatic scale; and keys for normally retaining certain of the vents closed, said keys and vents being 130

so positioned and grouped on the tube relative to each other that all the normally open vents can be simultaneously closed by one hand and separately closed and opened by such hand and all the normally closed vents can be simultaneously opened by such hand and can be controlled successively or in groups by such hand.

Having pointed out the broad feature of novelty, I do not wish to be limited to any specific construction or arrangement of the vents and keys; for the positions of the vents along the tubes are determined by the laws of acoustics and it is possible that those skilled in the art may change the grouping of the keys without departing from the broad spirit of this invention.

It is observed that in either tube the rims as at 90 and 108 of the digitally controlled vents constitute parts upon which the fingers press for controlling the digitally controlled vents *c* and *B*, respectively; and, likewise, the finger pieces for the key-controlled vents constitute parts as at 112, 113, 115, 117 upon which the fingers press for controlling such key-controlled vents, and that the parts provided on or in the pipe to receive the pressure of the fingers for controlling all the vents of such tube, whether key-closed or finger-closed, are located within the reach of the one hand that is used on such tube to play the full chromatic scale thereof of two or more octaves.

The finger-pieces for controlling the vents for notes *G*, *A*, *d* and *e* in Fig. 1; *d*, *e*, in Fig. 6 and *G*, *A*, in Fig. 7 are ring finger-pieces and said vents are digitally closed in the usual manner well understood, in the ordinary playing of the instrument. *f*, Fig. 6 is played by releasing ring *e* and closing *d*. *c*, Fig. 7, is played by releasing *b* and closing *a*.

I claim:

1. A mouth-blown musical pipe instrument comprising two tubes each having normally open and normally closed vents for a full chromatic scale of two or more octaves, said pipe being provided with parts upon which the fingers press for controlling the vents; such finger-receiving parts for the normally open vents being located so close together that all the normally open vents of the same tube can be simultaneously closed by the one hand for which such tube is fitted, and such parts for the normally closed vents being grouped together so that said normally closed vents of such tube can be successively opened by shifting the finger of the hand while said normally open vents are closed by such hand.

2. A mouth-blown musical pipe instrument comprising two tubes each having normally open and normally closed vents for a full chromatic scale of two or more octaves, said pipe being provided with parts upon

which the fingers press for controlling the vents; such parts for the normally open vents being located close together so that one hand can simultaneously close all the normally open vents of one tube, and such parts for the normally closed vents being located close together and comprising keys having finger pieces that are overlapped so that the normally closed vents can be successively played by shifting the finger of one hand over the finger pieces of such keys successively.

3. In a mouth-blown musical pipe instrument, two tubes each provided with vents and keys arranged to play a full chromatic scale of two or more octaves and to be played by one hand; a single mouth-piece fitted to said tubes and provided with two mouths; reeds for said mouths, and a rib between the reeds of said mouths to prevent escape of wind, so that said reeds may be properly vibrated.

4. A mouth-blown musical pipe instrument comprising a tube having normally open and normally closed vents arranged to produce a full chromatic scale of more than one octave so positioned and arranged and provided with keys substantially as set forth that all of the normally open vents can be simultaneously closed by one hand and the normally closed vents can be successively opened by the fingers of the same hand.

5. A mouth-blown musical pipe instrument comprising a tube having normally open and normally closed vents arranged to produce a full chromatic scale of more than one octave so positioned and arranged and provided with keys that all the normally open vents can be simultaneously closed by one hand and the normally closed vents can be successively opened by said hand; some of the keys being grouped and overlapped for successive playing by shifting the fingers substantially as set forth.

6. A mouth blown musical pipe instrument comprising a taper bore tube, a cylindrical bore tube, and a mouth piece to introduce air simultaneously into both of said tubes from the player's mouth; both said tubes being provided with vents and keys to produce any two notes of two musical scales simultaneously.

7. A mouth blown musical pipe instrument comprising a taper bore tube, a cylindrical bore tube, and a mouth piece to introduce air simultaneously into both of said tubes from the player's mouth; both of said tubes being provided with vents and keys to produce two notes of two chromatic scales simultaneously.

8. A mouth blown musical pipe instrument comprising a taper bore tube, a cylindrical bore tube, and a single mouth piece having two mouths and fitted to said tubes; said tubes being provided with vents and

keys for sounding any two notes of two chromatic scales simultaneously.

9. A musical reed instrument comprising two pipes and a mouth piece for said pipes; 5 said mouth piece being provided with two mouths; and reeds fixed to the outside of said mouths; the portion between said mouths being formed to prevent passage of wind therebetween.

10. A musical reed instrument comprising two pipes each provided with vents and keys for a full chromatic scale of two or more octaves, the vents of each pipe being arranged to be played by one hand, and a 15 single mouth piece having two mouths and reeds therefor and also having two channels communicating between said mouths and the bores of the two pipes respectively, the portions between said mouths being 20 formed to prevent the passage of wind therebetween.

11. A musical reed instrument comprising two pipes and a mouth piece for said pipes; said mouth piece being provided with two 25 mouths; reeds fixed to the outside of said mouths, and a rib between the reeds to prevent the passage of wind between said reeds.

12. A musical reed instrument comprising a clarinet-mouthpiece having two openings and two pipes connected to the two openings respectively of said mouth-piece, the portion between said openings being formed to prevent the passage of wind between said two openings.

13. A musical mouthblown instrument having two tubes each provided with vents and keys, and adapted to be simultaneously played by the performer's hands to produce any two notes of a chromatic scale simultaneously independent of one another; said tubes having a cylindrical and a tapering bore respectively.

14. A mouthblown musical pipe instrument comprising a tube having normally open and normally closed vents arranged to produce a full chromatic scale of more than one octave; said pipe also having parts upon which the fingers press for controlling said vents; the parts upon which the fingers 45 press for controlling the normally open vents being located so close together that such vents can be simultaneously closed by one hand; and keys for the normally closed vents; the finger pieces for said keys being 50 grouped together so that the normally closed vents can be successively opened by the fingers of the same hand.

15. A mouth-blown musical pipe instrument comprising a tube having normally open and normally closed vents arranged to produce a chromatic scale of more than one octave; the said pipe also having parts upon which the fingers press for controlling the vents; such parts for the normally open 65 vents being located so close together that the

normally open vents can be simultaneously closed by one hand; and keys for the normally closed vents; the finger pieces for said keys being grouped together and overlapped so that the normally closed vents can be 70 simultaneously opened by said one hand.

16. A mouth-blown musical pipe instrument comprising a tube having normally open and normally closed vents arranged to produce a chromatic scale of more than one 75 octave; said pipe also having parts upon which the fingers press for controlling the vents; such parts for the normally open vents being located close together so that the normally open vents can be 80 simultaneously closed by one hand; and keys for the normally closed vents having finger pieces grouped together and overlapped so that they can be successively played by shifting one finger of said 85 one hand.

17. A mouthblown musical pipe instrument comprising two tubes, vents for said tubes capable of producing two chromatic scales of more than one full octave simultaneously, two sets of keys independent of 90 one another, one set for each tube; the set for one tube normally closing the vents of the upper section of such tube, vents of the lower section of such tube being digitally 95 closed.

18. A mouth-blown musical pipe instrument comprising a taper bore tube having normally open and normally closed vents arranged to produce a full chromatic scale of 100 more than one octave; said pipe also having parts upon which the fingers press for controlling the vents; the parts for the normally open vents being located so close together that said normally open vents can be simultaneously closed by one hand, and keys for the normally closed vents having finger pieces grouped together and overlapped so that they can be successively played by one 105 finger of said one hand.

19. A mouth-blown musical pipe instrument comprising two tubes each having normally open and normally closed vents for a full chromatic scale of more than one octave; said pipe also having parts upon which the fingers press for controlling the vents; the parts upon which the fingers press for controlling the normally open vents being located so close together that all the normally open vents can be simultaneously closed by 110 one hand; the normally closed vents of the upper section of the right hand tube and vents of the lower section of the left hand tube being provided with keys, the finger pieces of said keys being grouped together 115 so that said normally closed vents can be successively opened by one finger of said one hand, said tubes having a cylindrical and a tapering bore respectively.

20. A mouth-blown musical pipe instru- 120

- ment comprising a tapering bore tube having normally open and normally closed vents arranged to produce a full chromatic scale of more than one octave, said pipe also having parts upon which the fingers press for controlling the vents; the parts upon which the fingers press for controlling the normally open vents being located so close together that said normally open vents can be simultaneously closed by one hand; and keys for the normally closed vents; the finger pieces of said keys being grouped together and overlapped so they can be simultaneously opened by said one hand.
21. A mouthblown musical pipe instrument comprising two tubes each having digitally-controlled vents and key-controlled vents for a full chromatic scale of two or more octaves, some of said vents being normally open and others normally closed, the digitally-controlled vents and the keys of the key-controlled vents of each tube being located together for operation by one hand so that all the normally open vents of either tube can be simultaneously closed by one hand and the normally closed vents of the same tube can be successively opened by said one hand.
22. A mouthblown musical pipe instrument having two tubes, each having digitally-controlled vents and key-controlled vents including normally open and normally closed vents for a full chromatic scale of two or more octaves, the digitally closed vents and the keys of the key-controlled vents of each tube being located together within the range of the fingers of one hand so that all the normally open vents of either tube can be simultaneously closed by one hand and the normally closed vents of either tube can be successively opened by said
- hand; some of the keys being grouped and overlapped for successive playing by one finger substantially as set forth.
23. A mouthblown musical pipe instrument comprising a tube having digitally-controlled vents and key-controlled vents for a full chromatic scale of more than one octave, some of said vents being normally open and others normally closed, the digitally-controlled vents and the finger pieces for the key-controlled vents being located together for operation by one hand so that all the normally open vents of a full chromatic scale of more than one octave can be simultaneously closed by one hand and the normally closed vents can be successively opened by said one hand.
24. A mouthblown musical pipe instrument having a tube, said tube having digitally-controlled vents and key-controlled vents including normally open and normally closed vents for a full chromatic scale of more than one octave, the digitally-controlled vents and the finger pieces of the key-controlled vents being located together within the range of the fingers of one hand so that all the normally open vents can be simultaneously closed by one hand and the normally closed vents can be successively opened by said hand; some of the keys being grouped and overlapped for successive playing by shifting the finger substantially as set forth.
- In testimony whereof, I have hereunto set my hand at Los Angeles, California, this 10th day of April, 1913.
- NIKLAS SCHILZONYI.
- In presence of—
 JAMES R. TOWNSEND,
 L. BELLE WEAVER.
